UNITED STATES PATENT OFFICE.

OLAF HETLESAETER, OF MILWAUKEE, WISCONSIN, ASSIGNOR TO ALLIS-CHALMERS COMPANY, OF MILWAUKEE, WISCONSIN, A CORPORATION OF NEW JERSEY.

EXCAVATING-MACHINE.

No. 899,597.

Specification of Letters Patent.

Patented Sept. 29, 1908.

Application filed February 4, 1907. Serial No. 355,607.

To all whom it may concern:

Be it known that I, OLAF HETLESAETER, a citizen of the United States, residing at Milwaukee, in the county of Milwaukee and State 5 of Wisconsin, have invented a certain new and useful Excavating-Machine, of which the following is a specification.

This invention relates to excavating machines in which a carrier provided with 10 excavating apparatus is also provided with a steady member or members to take the strains imposed upon the apparatus while at work, and it relates specifically to specific forms of spuds and means for operating them, 15 which, as far as the broad features of this invention are concerned, are capable of use either with a floating carrier or scow, or with a land vehicle, as with a railroad car or common cart.

20 In the drawings which accompany this specification and form a part thereof and on which the same reference characters indicate the same elements in each of the several views of the drawings, and which drawings 25 illustrate this invention as applied to a dredge, a scow or pontoon being illustrated as the carrier,—Figure 1 represents a vertical elevation of the dipper end of the dredge; Fig. 2 represents a plan view of the same end 30 of the dredge; and Fig. 3 represents an elevation of the same end of the dredge, the view being taken from a point at one side of the dredge.

The reference character 1 designates a 35 scow or pontoon which is adapted to carry the excavating machinery, and in Figs. 1 and 3 the scow is shown as floating in a body of water 2, adjacent a bank 3, upon which bank it is proposed to deposit the material re- 40 moved by the dipper 4 from the bottom of the cut 5.

It is customary with excavating machinery of the general nature disclosed by the drawings forming a part of this specification to 45 use spuds or their equivalent for taking the strains from the carrying member and also for rigidly supporting said carrying member.

This invention is designed to provide 50 spuds which are adapted to be used under varying conditions of work and to provide such spuds with means for readily, positively and cheaply operating them.

55 Referring to the drawings, the numeral 6 represents the A-frame which may be of any ordinary or preferred construction and which is secured to the scow in any preferable man-

ner, as by the rockers 7, being supported in position by the back stay 8 and supporting by the flexible member 9 the boom 10, which boom is in turn supported by the turntable 60 11, which arrangement of parts may be of any preferred construction or type.

In the apparatus as shown, the A-frame 6 is projected forward so that its upper end is over the center of rotation of the turntable 65 11, and on the upper end of the A-frame is carried a rotatable pulley 12, around which is carried the flexible member 9, which is then secured to the boom by the links 13 and 14. By this arrangement the boom is free to 70 be swung by the turntable either towards the right or the left hand side of the scow without any tendency to tip the boom and cause the parts to bind while they are operating.

The numeral 15 designates in general the 75 winding drums of any ordinary or preferred type of hoisting engine, the engine itself, boiler and accessories not being shown.

Carried by and supported from the boom 10 is the bucket 4 carried by the arm 16, 80 which bucket is manipulated by the customary hoisting rope or chain 17 and the back chain 18, both the hoisting rope and back chain being led to the hoisting drums of the engine to which are also led the rope or chain 85 19 by which the turntable is operated, all of these parts being of any ordinary or preferred construction.

Located preferably above the turntable and beneath the overhang of the A-frame and 90 securely fastened to the body of the scow, is the gantry or gallows frame which is composed of uprights 191 and 20 across the tops of which is the cross beam 21, which preferably is arranged to extend outwardly some 95 distance beyond each side of the scow, and the overhanging ends of which may be braced by the braces 22.

Secured adjacent the uprights of the gallows frame is a member 23 provided with 100 apertured projections by means of which the spuds 24 may be movably connected with said member by the bolts 25. This member 23 preferably takes the form of a steel or iron strap bent to fit the cross section outline of 105 the scow, as clearly shown by Fig. 1 of the drawings, and after being placed upon the scow, the free ends of said member are connected by the tie bolts 26 which extend across the scow, this specific construction being 110 designed to relieve the body of the scow from any unnecessary strains. The over-

hanging ends of the cross beam 21 are provided with blocks 27 which may be composed of a plurality of pulleys, a single pulley being shown by the illustrations to avoid obscuring the details of the drawing.

The spuds proper which have been designated as a whole by the numeral 24, are preferably triangular in form, being composed of the members 28, 29 and 30, rigidly secured together and movably secured to the scow by the bolt 25, one apex of the triangle of the spud being provided with a foot or sole piece 31 pivotally secured to the spud members by the bolt 32. The triangular construction gives great rigidity to the spud. The angle between the members 29, 30, prevents coincidence of the operating cable and either of these parts and consequent locking effect due to "dead center".

Secured to the lower and outboard end of the spud is a pulley 33. Rigidly secured to the cross beam 21 is the standing end of a rope or flexible member 34 which passes downwardly around pulley 33, upwardly around pulley 27, inwardly around the fair leader or pulley 35, around the winch 36 of the winding engine with several turns on said winch, back around the fair leader or pulley 37, around the pulley 38 and to pulley 39, which latter pulley is secured to the upper apex of the triangle formed by the spud members, and is then secured firmly to the cross beam 21 at 210. The operation of this part of the apparatus is as follows: If it is desired to lower the spud shown at the left hand of Fig. 1 so that the shoe will rest on the bottom of a canal or excavation, the winding engine is started and the winch 36 is turned to pay out on the running part of the rope 34 which passes around the pulley 33. At the same time that the rope is being paid out which passes around the pulley 33, the other end of the rope is being gathered in upon the winch 36, and when the shoe 31 takes upon the bottom of the excavation it is the pull upon this other end of the rope which passes around the pulley 39 which gives the lifting power, or, in other words, the bearing down power on the spud. If it now becomes necessary to raise the same spud either to take it inboard for transportation, or to rest against a bank, as shown by the spud at the right hand side of said Fig. 1, the hoisting engine is started but it is reversed as to its direction of rotation so that now the rope 34 which passes around the pulley 33 is drawn in and around the winch, while the other end is slackened away.

The numeral 40 designates the tie ropes or

braces which are secured by universal joints 60 both to the spuds and the sides of the scow to prevent movement of the scow with respect to the spuds. The spud on the opposite side of the dredge is operated in a similar manner.

What I claim is,—

1. The combination with a carrier for excavating machinery or the like, of a bolt secured thereto, a spud pivotally mounted on said bolt and composed of members disposed at an angle with respect to each other, pulleys located in the angular space between said members, and flexible means secured to said members and passed over said pulleys for operating said spud.

2. The combination with a carrier for excavating machinery or the like, of a bolt secured thereto, a spud pivotally mounted on said bolt and composed of members disposed at an angle with respect to each other, pulleys located in the angular space between said members, a winch, and a flexible operating device secured to one of said members, passed over one of said pulleys, around said winch, over another of said pulleys and then secured to another of said spud members.

3. The combination with a carrier for excavating machinery or the like, of two bolts secured thereto, spuds pivotally mounted on said bolts, one spud on each bolt, each of said spuds being composed of members disposed at an angle with respect to each other, pulleys located in the angular space between the members composing said spuds, two winches, and two flexible operating devices, each of said devices being secured to one member of its respective spud, passed over a pulley, around a winch, over another pulley and then secured to another of its spud members.

4. The combination with a scow, of a metal strap bent to fit the cross section outline of the scow, a tie-bolt to secure said strap to said scow, and a spud secured to said strap.

5. The combination with a carrier for excavating machinery or the like, of a spud pivotally secured thereto, said spud being composed of arms disposed at an angle with respect to each other, flexible means secured to one of said arms for raising said spud, and flexible means secured to the other of said arms for forcing said spud down.

In testimony whereof, I affix my signature in the presence of two witnesses.

OLAF HETLESAETER.
